UNITED STATES PATENT OFFICE.

GEORGE D. MUNSON, OF WALLINGFORD, CONNECTICUT, ASSIGNOR TO INTERNATIONAL SILVER CO., OF MERIDEN, CONNECTICUT, A CORPORATION OF NEW JERSEY.

COMBINED CIGARETTE-CASE AND MATCH-BOX.

1,114,378.

Specification of Letters Patent.

Patented Oct. 20, 1914.

Application filed May 25, 1914. Serial No. 840,843.

To all whom it may concern:

Be it known that I, GEORGE D. MUNSON, a citizen of the United States, residing at Wallingford, in the county of New Haven 5 and State of Connecticut, have invented a new and useful Improvement in Combined Cigarette-Cases and Match-Boxes; and I do hereby declare the following, when taken in connection with the accompanying drawings 10 and the characters of reference marked thereon, to be a full, clear, and exact description of the same, and which said drawings constitute part of this application, and represent, in—

15 Figure 1 a side view of a combined cigarette case and match box constructed in accordance with my invention. Fig. 2 a sectional view on the line *a—b* of Fig. 1. Fig. 3 an inside view of the case in the open position. Fig. 4 a broken sectional view illustrating how the spring arms are mounted on the hinge pin. Fig. 5 a sectional view on the line *c—d* of Fig. 1.

This invention relates to a combined cigarette case and match box, the object being to provide suitable compartments for cigarettes with spring pressed arms to hold them in place, and a match box located within the cigarette case and provided with an independent cover; and the invention consists in the construction hereinafter described and particularly recited in the claim.

In carrying out my invention, the case is formed from two members 2 and 3 preferably bowed transversely. These members are provided, respectively, one with knuckles 4 and the other with knuckles 5 through which a pin 6 extends, whereby the members are hinged together. Upon this pin are 40 mounted arms 7 and 8 and having tubular portions 9 and 10 which surround the pin 6, which tubular portions are larger in diameter than the pin to provide for the introduction of a spring 11 one end of which 45 bears upon the tubular portion 9 and the other end bears upon the tubular portion 10, the tendency of the spring being to force the arm 7 into the member 2 and the arm 8 into the member 3, this spring pressure tending to throw the case open when released by

the latch 12 mounted in the member 3 and adapted to engage with the flange 13 of the member 2. In the lower end of one of the members, and as herein shown, the member 3, is a compartment 14 formed by the introduction of a rectangular wall 15 which wall extends slightly above the walls of the member 3 so as to form a comparatively deep box for matches. This match box is closed by a cover 16 the cover and box being provided respectively with knuckles 17 and 18 through which a pin 19 extends, and this pin is fixed at one end to a knuckle on the box and at the opposite end to a knuckle on the cover so as to form a spring to hold the cover in closed position. The central portion of the cover is cut away to form a clearance opening 20, and on the inner face of the cover across the opening is an offset strip 21 forming a space for the introduction of a strip 22 of abrading material the surface of which is exposed to the opening 20 in the cover. The upper wall of the match box forms the lower wall of a compartment 23 for cigarettes which are held in place by a finger 8, while the member 2 is furnished with a partition 24 substantially in line with the top of the match box and forming a compartment 25 for cigarettes which will be held in place by a spring finger 7. The match box projecting beyond the member 3 and so as to enter the member 2 when the case is closed, forms a stop to prevent lateral play, and to a certain extent relieves the strain which might be imposed upon the hinge pin. I thus provide a cigarette case with two compartments for cigarettes and an independently inclosed match box.

I claim:—

A combined cigarette case and match box comprising two members connected together by a hinge pin, spring arms having tubular ends through which the pin extends, a spring within said tubular portion of the arms and surrounding the pin, one end of the spring bearing on one arm and the opposite end bearing on the other arm, a match box formed by a rectangular wall located in the lower end of one member beyond the

face of which it projects, a cover hinged to
said wall the central portion of the said
cover cut away, a strip secured to the inner
face of the cover and offset therefrom, there-
by providing a pocket, and a partition wall
located in the other member in line with
the upper edge of the said match box.

In testimony whereof, I have signed this
specification in the presence of two subscrib-
ing witnesses.

GEORGE D. MUNSON.
